(57) **CLAIM**

The ornamental design for a sink filter device, as shown and described.

DESCRIPTION

FIG. 1 is a front side perspective view of a sink filter device showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1; and,

FIG. 8 is another side perspective view of FIG. 1.

The dashed broken lines depict portions of the sink filter device that form no part of the claim.
